UNITED STATES PATENT OFFICE.

CHARLES L. WAGANDT, OF BALTIMORE, MARYLAND, ASSIGNOR TO NATIONAL ENAMELING AND STAMPING COMPANY, OF NEW YORK, N. Y., A CORPORATION OF NEW JERSEY.

OIL STOVE.

Application filed June 26, 1922. Serial No. 570,924.

To all whom it may concern:

Be it known that CHARLES L. WAGANDT, a citizen of the United States, residing at Baltimore, in the State of Maryland, has 5 invented certain new and useful Improvements in Oil Stoves, of which the following is a specification.

This invention relates to improvements in oil stoves and has reference to a stove utilizing a wick and burning oil for either heating or cooking purposes.

One object of the invention is to provide an improved construction of stove wherein a metal cylinder or chimney is employed 15 whereby the chimney may be readily moved from one position to another to permit access to the burner without detaching the chimney.

Another object of the invention is to provide improved means for pivotally sustaining 20 the chimney whereby the latter may be made to assume either of three positions, to wit: seated over and in alignment with the burner; partly tilted to permit access 25 to the burner and wick so the same may be cleaned, trimmed or ignited, or completely swung back to permit the oil receptacle or fount and burner to be removed without detaching the chimney.

30 A further object of the invention is to provide improved means for sustaining the stationary top from the base but permit the independent movements of the chimney to be made.

35 With these, and other objects in view, the invention is illustrated in the accompanying drawing, wherein,—

Fig. 1 shows the improved stove in front elevation.

40 Fig. 2 illustrates the base and chimney in top view but shows the supporting structure for the top in cross-section,—the latter being sectioned substantially on the line 2-2 of Fig. 1.

45 Fig. 3 shows the stove in central vertical section,—the chimney being illustrated in full lines in a partly tilted position and by broken lines in the fully tilted position, and

50 Fig. 4 illustrates an enlarged vertical cross-sectional detail through the improved hinge device which carries the chimney.

Referring to the drawings the numeral 6 designates an annular sheet-metal base having a plurality of feet 7 formed integrally therewith and provided in its top with

a circular opening 8, which latter can be clearly seen in Fig. 3 of the drawings.

At each side of the base there is provided a vertical supporting plate 9. Each of these plates is curved in a horizontal direction 60 and each is therefore a segmental plate in that it extends part of the way only around the top of the base.

The front and rear vertical edges of these segmental plates are formed into rolls or 65 coils 10 so that vertical rods 11, may extend through the base and pass through the rolls or coils 10 as and for a purpose that will presently be explained.

It is to be particularly noted that the positions of these segmental plates with respect 70 to each other is such that a vertical front opening 12 and a vertical rear opening 13 are formed,—the front opening extending from the base upwardly.

It will also be noted that the front opening 12 in this instance is of a greater width than the rear opening, for a purpose that will also presently be explained.

Immediately above the base and at the 75 rear, there is provided a cross-plate 14 whose ends are coiled or rolled at 15, so as to engage the two vertical rear coils 10 of the segmental plates 9.

The upper edge of this cross-plate has an 80 inturned flange 16 to reinforce and stiffen the same.

The vertical segmental plates 9 sustain a top plate 17, which latter seats thereon and the rods 11 which pass through the coils 90 10 also pass through the top plate and have heads 18, which seat down on the upper side of said plate while the lower ends of said rods beneath the base are provided with nuts 19, as shown in broken lines in Fig. 3, which nuts draw the rods down and clamp the segmental plates 9 between the top plate 17 and the base.

It will thus be understood that the base 6, the segmental plates 9 and the top plate 100 17 are all rigid and permanently connected by means of the four rods 11, and constitute the supporting structure, and also that this structure has a front vertical opening and also a rear vertical opening.

The top plate 17 is provided with any 105 desired form of perforations or openings 20 and also preferably has a series of raised ribs 21, on which a receptacle to be heated may be placed.

A suitable handle 22 is also provided at the top by means of which the stove may be lifted or carried from place to place.

In the present instance the heating medium is to be oil and with this in view there is provided an oil fount or container 23, which depends through the opening 8 in the top of the base and seats thereon in the usual way. This reservoir carries the 10 usual annular gallery 24 on which a cylinder or chimney 25, may seat to cover or encircle the burner 26.

One of the features of the present invention lies in the fact that the cylinder or 15 chimney which seats around and extends above the burner is permanently attached to the supporting structure, but is so carried, that it may be swung backwardly and held in either of two tilted positions. When in 20 one of these two positions, to wit, that shown in full lines in Fig. 3, the chimney will uncover the burner and wick so the same may be exposed for cleaning, trimming or igniting, whereas when the chimney is 25 swung backwardly as far as it will go, as shown in broken lines in Fig. 3, its lower end will be entirely removed from over the burner and fount, so the latter can be lifted out from the base for cleaning or refilling. 30 These movements of the chimney may be made without detaching the same and these features in operation, together with the means employed to effect them, are novel with me.

By reference to Figs. 3 and 4 of the drawings it will be noted that against the rear face of the cross-plate 14 there is seated a bracket-plate 27 which plate is rigidly secured to the cross-plate by means of rivets 40 28 which pass through perforations 29 in the bracket-plate and extend also through the metal of the cross-plate. This bracket-plate has a forwardly-extending horizontal flange 30 which projects over the inturned 45 reinforcing flange 16, on the upper edge of the cross-plate.

At each side, the bracket-plate is provided with an upwardly-extending arm or lug 31, which arms or lugs also extend outwardly or rearwardly and in a direction reverse to that in which the flange 30 extends. The arms or lugs project above the said horizontal flange 30, for a purpose that will presently be described.

55 A hinge-plate 32, having an up-turned flange 33, at each side thereof, has its outer end located between the two vertical arms or lugs 31 so that a horizontal pivot-pin or bolt 34 may be passed through said arms and flanges to pivotally sustain said plate near said outer end.

This hinge plate 32, normally has a substantially horizontal position and seats on the upper side of the flange 30 of bracket-plate 27. The outer end, however, of said

hinge plate, projects over the outer side of said flange while the inner end thereof projects at the inner side of said flange, as clearly shown in either Fig. 3 or Fig. 4 of the drawing.

70 It will also be noted that the pin or bolt 34, has position in a vertical plane beyond the outer side of the flange 30 and its bracket-plate 27, so that when said hinge-plate 32, is turned on the pin, as shown in Fig. 3, 75 its outer edge 35 will strike the rear face of the bracket-plate and be stopped against further movement.

The inner forward edges of the up-turned flanges 33 of the hinge-plate are beveled or so inclined as at 36 and immediately below said beveled edges the flanges have pivot-holes or perforations 37. When the hinge-plate 32 is in the normal substantially horizontal position it will project forwardly 85 through the rear opening 13 of the supporting structure and over the fount 23, as shown in Figs. 2 and 3 of the drawing.

The cylinder or chimney 25 has a bracket-plate 38, attached thereto and each end of this bracket-plate has a rearwardly-extending ear 39 between which latter the inner forward end of the hinge plate flanges 33 project. A pin or rod 40, extends through said ears 39 and the perforations 37 in the hinge-plate flanges so as to pivotally connect the cylinder with the forward end of the hinge-plate.

It will thus be seen that the cylinder 25, 90 is pivotally carried at the inner forward end of the hinge-plate 32 and that the hinge plate has its rear outer end pivotally sustained from the bracket-plate 27.

By this construction the cylinder 25, may be tilted back through the rear opening 13, 105 by swinging on the forward end of the hinge-plate, as shown in full lines in Fig. 3, and when so tilted will permit access to be had to the burner 26 for lighting or trimming. It will also be noted that both the cylinder and the hinge-plate may be swung together on the pivot 34 whereby to completely swing the cylinder through the rear opening so that the lower end of the chimney will be entirely removed from over the burner and fount 23, so the latter may be 115 lifted and removed through the forward opening 12,—the complete rearward movement of the cylinder and hinge-plate being shown in broken lines in Fig. 3.

120 It will thus be seen that the double-hinge structure, by which the cylinder or chimney is sustained, ensures that the chimney will always be properly guided when swung over the burner and will be accurately seated about the burner; that the chimney may readily be tilted back to expose the burner and be held in that partially tilted position, and that the said chimney may be tilted back to a further degree to remove the lower 130

end from over the burner and fount in order that the latter may be lifted out of the base-opening for cleaning, filling or other purposes.

5 Having described my invention, I claim,—
 1. In an oil stove the combination with a base of supporting means extending upwardly from opposite sides of the base and spaced at both the front and rear to form a 10 front and a rear vertical opening, a top rigidly attached to the supporting means and extending over said front and rear openings, a fount carried by the base, a cylinder between the opposite supporting 15 means and means for pivotally sustaining the cylinder so it may swing through the said rear opening.

2. In an oil stove the combination with a base, of a fount carried by the base, supporting means extending vertically at opposite sides and at the rear from said base said rear portion of the supporting means being of a less height than the opposite side portions of the said supporting means 25 whereby to provide a vertical rear opening between the side portions of the supporting means, a top supported on the side portions of the supporting means and covering the rear opening, and a cylinder pivotedally sustained from the lower rear portion of the said vertical supporting means so it may be swung rearwardly over said lower portion and through the said rear opening.

3. In an oil stove the combination with a base of supporting walls extending upwardly from the base at opposite sides and at the rear and spaced to form a front opening and further spaced to provide a rear vertical 40 opening, a top rigidly attached to the supporting means and covering the front and rear openings, a fount carried by the base, a cylinder above the fount and a hinge at the rear opening of the supporting 45 means and pivotally engaging the said cylinder whereby the cylinder may be swung back through the rear opening of the said supporting means to uncover the fount.

4. In an oil stove the combination with a 50 base of a supporting means extending upwardly from the base and spaced to form a front and a rear vertical opening, a top rigidly attached to the supporting means and extending over the front and rear openings, a cylinder above the fount and between the supporting means, a hinge pivotally attached to the supporting means and means

for pivotally connecting the cylinder to the hinge whereby the cylinder may be tilted on its pivot connection with the hinge and the hinge may be swung on its pivot with respect to the supporting means.

5. In an oil stove the combination with a base, of two spaced-apart segment plates extending vertically from the base and each 65 plate having a tubular formation at its front and rear vertical edges, a top above the segment plates, rods extending through said tubular formations and connecting the base and top, a fount carried by the base, and a 70 cylinder between the segment plates and over the fount.

6. In an oil stove the combination with a base, of a top, spaced-apart vertical plates between the base and top and supporting 75 the latter, a fount carried by the base, a hinge-plate pivotally carried with respect to the vertical plates, a cylinder pivotally attached to the hinge-plate whereby the cylinder may have a preliminary movement 80 with respect to the hinge-plate and a further movement with the hinge-plate.

7. In an oil stove the combination with a base, of a supporting structure extending upwardly from the base and having a front 85 opening and a rear vertical opening, a top rigidly carried on the supporting structure, a fount carried in the base, and a hinge device having one end pivotally attached to the supporting structure at the said rear opening and its other end pivotally attached to the cylinder whereby the cylinder may be partly tilted back into the rear opening and may be further tilted through said opening.

8. In an oil stove the combination with a base, of a top sustained in an elevated position above the base so as to provide a front vertical opening and a rear vertical opening, a fount carried by the base, a cylinder between the fount and the top and a double hinge device having two pivot points said hinge having a member rigid with respect to the base and another member rigidly attached to the cylinder whereby the cylinder 105 may be tilted on one of the hinge-pivots into the rear opening for certain purposes and the cylinder and a portion of the hinge tilted on the other hinge-pivot to swing the cylinder further through the rear opening to permit the fount to be lifted and removed through the front vertical opening.

In testimony whereof I affix my signature.
 CHARLES L. WAGANDT.
